UNITED STATES PATENT OFFICE.

THEODORE H. CHAMPION, OF MINNEAPOLIS, MINNESOTA.

BLOWER FOR BOILER-FURNACES.

SPECIFICATION forming part of Letters Patent No. 393,357, dated November 27, 1888.

Application filed May 25, 1888. Serial No. 275,075. (No model.)

To all whom it may concern:

Be it known that I, THEODORE H. CHAMPION, a citizen of the United States, and a resident of the city of Minneapolis, county of 5 Hennepin, State of Minnesota, have invented a certain new and useful Improvement in Blowers for Boiler-Furnaces, of which the following is a specification, reference being had to the accompanying drawings.

10 My invention is in the nature of an improvement on the mechanism shown and described in the Patent No. 362,935, issued to me, of date May 17, 1887. By reference to that patent it will be seen that I introduce a mass of thoroughly-commingled air and steam under the 15 furnace-grate. The steam is taken from the steam-dome of the boiler and the air from any convenient location outside the furnace. A peculiar injector, consisting of a number of 20 truncated cone-shaped nozzles, is set in an annular steam-pipe, with their large ends outermost, and over each nozzle is placed a truncated cone-shaped hood, with its large end surrounding the large end of the steam-nozzle. 25 The result is that the steam passes out on divergent lines and the air enters the hood on convergent lines, and the two are thoroughly commingled. A large conical-shaped shell encircles the injector, with its small end toward 30 the furnace-grate, and is adjustable lengthwise, for the purpose of varying the focus or converging point of the commingled mass of air and steam. The whole mass of air and steam is thus forced under the grate under 35 high pressure, and is found very effective in assisting to burn slack and other forms of refuse fuel. Provision is made for drawing the steam either directly from the boiler to the injector, or for superheating the steam before 40 it is passed to the injector. This construction makes a very powerful blast and quickly raises the fire to an intense heat. It is therefore desirable to only employ the blast intermittently.

45 My present invention has for its object to make the construction self-regulating. A certain pressure is adapted as the standard, and whenever the pressure in the boiler falls below this point the blast is turned on. When it 50 rises to the standard pressure, it is automatically cut off.

To this end my invention consists in the con-

struction hereinafter described, and particularly pointed out in the claims.

In the drawings, like letters referring to like 55 parts throughout, Figure 1 is a side elevation; Fig. 2, a vertical cross-section; Fig. 3, a plan of a furnace-boiler embodying my invention, and Fig. 4 is a vertical section of the pressure-regulator.

60

A is the body of the furnace; B, the fire-box or combustion-chamber; C, the grate; D, the ash-pit; E, the boiler; F, the steam-dome of the same.

G is a blast-conduit cut through one of the 65 walls of the furnace, leading to the interior of the ash-pit.

H is my combined air and steam injector, of a construction described in my former patent.

H' is the steam-supply pipe connecting the 70 injector with the steam-dome of the boiler.

h is a stop-cock in this pipe for regulating the supply of steam by hand, if so desired. Injector H is in the mouth of conduit G.

J is a fixed support at some point above the 75 boiler. It may be the ceiling of the boiler-room. One or more sheaves, i, are attached to the support J. In the pipe H', preferably on the horizontal section of the same and in proximity to the steam-dome, is placed a cut-off and supply valve, K, having a stem projecting therefrom through a suitable stuffing-box, k. A pair of arms, l l', are rigidly attached to the pipe or to a sleeve mounted thereon on the opposite sides of the stuffing-box. One of these arms, as l', is bifurcated and extended to some little distance above the other arm, l.

L is a lever pivoted to the arm l at one end, and bearing an adjustable weight, M, on its 90 other or free end. This lever is held and guided between the bifurcated ends of the arm l'. The stem of the valve K is attached to the lever L between the arms l and l'.

N is the regulator. It may be of any suitable construction adapted to the purpose, and controlled either by water or steam from the boiler. The construction shown is adapted to steam; and it consists, essentially, of a fixed hollow piston having a small exhaust-duct, a 100 movable cylinder mounted thereon, and a balanced valve for controlling the supply of steam to the interior of the piston. To a right-angled extension, a, of the steam-supply pipe

b, I attach a valve-seat section of pipe, 1, provided with the valve-seat 2 and an exhaust-duct, 3, leading from a point above the valve-seat. Into the top of the valve-seat section I screw a solid section, 4, provided with a vertical steamway, 5, on one side, and a central slot, 6, for the passage of the valve-operating lever P, and a hollow axis below said slot for the outward passage of the valve-stem. 10 7 is the balanced valve located in the seat 2 and connected to the lever P by the stem 8. 9 is the hollow open-ended piston, connected by the hollow stem 10 with the top of the intermediate section, 4. c is a weighted movable cylinder mounted thereon.

11 is a cushioning-spring within the piston and bearing against the upper end of the cylinder, and 12 is a similar spring encircling the piston-stem between the bottom of the cylinder and lower end of the piston. The exhaust-duct 3 is small compared with the steam-way 5, and communicates with a waste-pipe. (Not shown.) The exhaust-duct or waste-pipe may be supplied with a check-valve, if so desired; but such a valve is not necessary. The lever P passes through the slot C, and is fulcrumed at one end to some fixed support.

The valve-stem is attached to this lever. On the outer end of the lever is an adjustable weight, p. The action of this valve is that of the ordinary balance-valve. Whenever the steam in the boiler reaches a certain pressure, it will lift the weighted valve and pass into the cylinder c. This predetermined pressure may be fixed at any standard by varying the position of the adjustable weight.

35 From the top of the movable cylinder c a flexible connection, Q, extends over the sheaves i, and thence to the free end of the lever L.

40 R is the air-supply conduit communicating below with the blast-conduit G and having its receiving end at or near the top of the furnace-wall. I form this conduit by thick brick walls built out from the adjacent furnace-wall, 45 making the furnace-wall serve as the inner vertical wall of the conduit; or it may be described as set in the furnace-wall, which is enlarged for the purpose. The outer vertical wall, g, of this conduit is provided with a horizontal opening, S, at the bottom on a line with the blast-conduit G, for affording access to the injector, and with a door, T, for closing the same. The conduit R is provided with a gravity falling valve or door, W, at its top.

55 The flexible connection Q is provided with an extension, Q', attached to the free end of the door W; or the connection may be from the door W to the free end of the lever L.

The movable cylinder c is made of sufficient 60 weight or put under sufficient tension by springs to overcome the combined weight of the loaded valve K and the door W in the absence of steam in its interior; hence as long as the boiler-pressure remains below the predetermined standard the door W and the valve K will be raised and steam and air will be supplied to the injector and forced under

the grate. As soon, however, as the steam-pressure reaches the given standard it will overcome the weight p, raise the valve from its seat, and pass into the cylinder c. The cylinder will then rise under the steam-pressure, slackening the flexible connection, and the valve K and door W will fall to their limit by gravity, cutting off both steam and partially closing the air-conduit. The door W does not entirely close, leaving sufficient opening for supply of the natural draft. Thereafter the normal pressure will be maintained without material variation. The instant it falls below the standard the cylinder will descend and the valves be opened, admitting steam and starting the injector until the pressure is restored. When the mechanism is properly adjusted, the variation will be kept within a range of less than five degrees. This automatic regulation is a very material point in a blower of this kind. Otherwise the constant attention of an attendant would be required to turn on and off the supply of steam and air with all the concomitant risks of imperfect or defective control, not the least of which would be the frequent loss of his fire. With my regulator the fire is constant and the fuel is used with the greatest economy.

95 The purpose of having the receiving end of the air-supply conduit at or above the top of the furnace is to draw the supply from the hottest strata of air in the furnace-room. For the purpose of further heating this air the inner vertical wall of the conduit is passed as near as possible to the fire-wall of the furnace. Heat which would otherwise be wasted is thus utilized to raise the temperature of the air before it is brought in contact with the fuel, and a corresponding saving is effected.

100 The purpose of setting the injector within a space inclosed by heavy surrounding walls and having that part of the air-supply conduit directly connected to the injector formed with heavy surrounding walls is to deaden the sound of the blast. This effect is further heightened by having the receiving end of the air-conduit somewhat remote from the injector. Without some such provision the loud noise made is very objectionable.

105 It will, of course, be understood that the particular form of the automatic regulator is immaterial. All that is essential is, that the regulating device be operated by steam under boiler-pressure, and that the movable part of the device be connected in some suitable way with the valves controlling the supply of steam and air to the injector.

110 It is evident that springs might be substituted in place of the weights M and p.

I do not herein show any means for super-heating the steam before introducing it under the grate; but my construction for that purpose will be found fully set forth in my former patent, hereinbefore identified. My regulator is equally applicable in either case.

115 What I claim, and desire to secure by Letters Patent of the United States, is as follows:

1. The combination, with a steam-boiler furnace provided with a horizontal blast-conduit through one of its walls to the ash-pit, of a vertical air-supply conduit within the enlarged walls of said furnace adjacent to the combustion-chamber, having its receiving end at or above the top of the furnace, communicating below with said blast-conduit, and a combined steam and air injector within said blast-conduit having a steam-supply pipe communicating with the steam-space of the boiler, substantially as described.

2. The combination, with a steam-boiler furnace provided with a horizontal blast-conduit through one of its walls to the ash-pit, of a vertical air-supply conduit within the enlarged walls of said furnace adjacent

to the combustion-chamber having its receiving end at or above the top of the furnace and communicating below with said blast-conduit, a combined air and steam injector located in said blast-conduit having a valve in its steam-supply pipe, a valve in the receiving end of said air-supply conduit, and a pressure-actuated regulator having connections to said valves, substantially as described, whereby the supply of air and steam to the grate is automatically controlled by the pressure in the boiler.

THEODORE H. CHAMPION.
